UNITED STATES PATENT OFFICE.

GABRIEL TOTH AND EMANUEL A. BRANDT, OF FAR ROCKAWAY, NEW YORK.

HINGE.

Application filed April 9, 1926. Serial No. 100,815.

The invention relates to hinges and aims to provide certain improvements therein. More especially, it relates to hinges adapted for pivotally mounting screen frames upon window casements or frames.

Heretofore, the conventional practice in mounting so-called full length window screens has been to use the ordinary types of hinges, one leaf of which was first 5 screwed to the screen frame, after which the other leaf was fastened to the window frame so that the screen could swing outwardly with respect thereto. This practice necessitated the use of a ladder or a scaffold, since 10 the screen frame had to be mounted on the window frame from the outside, which practice was both hazardous and time consuming.

According to the present invention we provide a novel hinge through the use of which 20 a screen of the type described can be safely and quickly mounted on a window frame from the interior of a house. This hinge preferably consists of a pair of separable elements, adapted to be independently 25 mounted on the two parts which are to be connected together, and a separable pintle cooperating with said elements to hold them in assembled relation, whereby both a sliding 30 and swinging connection between the parts will result. An additional feature of 35 our hinge construction resides in the fact that the hingedly connected parts can be quickly disconnected without the aid of any tools whatever, since the cooperative engagement 40 of the pintle with the separable hinge elements is such that the pintle can be easily applied and removed by one's fingers. The invention also consists of other features of novelty which will be hereinafter more fully set forth.

In the accompanying drawings wherein we have shown by way of example a preferred embodiment of our invention,—

Figure 1 is a vertical section of a window 45 frame and screen mounted thereon by hinges of the present invention.

Fig. 2 is an enlarged view of the hinge mounting shown in Fig. 1.

Fig. 3 is a partial elevation of Fig. 1 50 viewed from the left thereof, the window sashes being omitted.

Fig. 4 is a composite view of the separate hinge elements shown in perspective.

Referring to the drawings wherein the 55 same reference characters indicate like parts in the various figures, let A indicate a win-

dow casement or frame within which are 60 slidably mounted the sashes B fitted with the window panes C, all of which may be of any conventional form.

Mounted within the window frame at the top thereof so as to swing outwardly is a so-called full length window screen consisting of a frame D and a wire mesh screen E. To hold the screen frame in place and against rattling any suitable means may be employed, such as a hook F fastened to the window sill and a cooperating screw eye f 65 screwed to the window frame.

According to the present invention the 70 screen is to be mounted on the window frame from the inside of the house and in order to accomplish this in a safe and efficient manner we have provided the novel hinge construction the component parts of which are best shown in Fig. 4. In its preferred construction this hinge consists of a pair of substantially U-shaped elements G and H the arms of which are formed with arcuate 75 openings g and h respectively, adapted to be brought into registry and a pintle I adapted to be passed through said openings to permit both a sliding and swinging action between said elements as best shown in Fig. 2. Preferably the pintle I is so formed as to be 80 capable of insertion and removal from the hinge elements by one's fingers without the aid of any tools whatever and after insertion to assume a position which would prevent its accidental withdrawal. This we accomplish by forming the openings g and h with enlarged portions g' and h' respectively and the pintle I with enlarged heads i adapted to pass through the enlarged portions of the 85 openings, after which the intermediate portion of the pintle I will seat in the smaller portion of the openings and be held therein against accidental removal.

In applying the hinge for use for the purpose described two elements G are first 100 screwed to the top of a window casement or frame at the edge thereof as best shown in Figs. 1, 2 and 3 by screw elements or the like passing through the openings g² in the base of the U-shaped members G. Two complementary elements H are then independently 105 mounted adjacent the top edge of the screen frame D by screws passing through the openings h² in the base of the elements, said elements being spaced apart the same distance as the elements G on the window frame. The screen frame is then taken from 110

the inside of the house, passed through the window frame and the elements H and G brought into cooperating position so that the openings g and h will be in registry.

- 5 The pintle I is then passed through the enlarged portions g' and h' of said openings and the intermediate portion of the pintle I then caused to seat in the smaller portion of the openings g and h. In this 10 position the screen frame will be adapted for both pivotal and sliding action with respect to the window frame as best shown in dotted lines in Figs. 1 and 2.

While we have shown and described our 15 novel hinge as adapted for use in mounting screens it will be apparent that its use is not to be so restricted since its applicability may extend to all devices wherein both a 20 sliding and swinging hinge action is desirable. It will also be understood that while we have shown and described a preferred embodiment of our invention we do not 25 wish to be limited to the specific form of hinge elements disclosed since modifications thereof may be resorted to without departing from the spirit of the invention.

Having shown and described our invention what we claim is:

1. A hinge comprising a pair of separable 30 substantially U-shaped members, the arms of said members being formed with elongated openings adapted to be brought into registry when the bases of said members are positioned at right angles to each other with the 35 adjacent longitudinal edges of said bases

in substantially abutting relation and a pintle adapted to engage in said openings and permit both a sliding and swinging action between said members.

2. A hinge comprising a pair of separable 40 U-shaped members, the arms of which are formed with arcuate openings larger at one end than the other adapted to be brought into registry and a pintle having enlarged 45 heads adapted to be passed through the enlarged portions of the openings and seat in the smaller portions of said openings and permit both a sliding and swinging action between said members.

3. A hinge comprising a pair of separable 50 U-shaped elements, the arms of which have elongated openings therein adapted to be brought into registry when the arms of one 55 of said elements are fitted within the arms of the other element, the openings in the outside element having corresponding portions thereof enlarged, and a pintle having enlarged heads adapted to be passed through the enlarged portions in said openings and 60 through the registering openings in the arms of the other U-shaped element in a direction lengthwise of the base of the U-shaped elements, the intermediate smaller portion of 65 said pintle being then adapted to seat in the smaller portion of the openings in the outside element to prevent the pintle from being accidentally withdrawn.
